(57) **CLAIM**

The ornamental design for a photo booth as shown and described.

DESCRIPTION

FIG. 1 is a front, left, top perspective view of a photo booth showing our new design;

FIG. 2 is a rear, right, top perspective view thereof;

FIG. 3 is a rear, right, bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged portion view taken from encircled portion “10,” in FIG. 1;

FIG. 11 is an enlarged portion view taken from encircled portion “11,” in FIG. 1;

FIG. 12 is an enlarged portion view taken from encircled portion “12,” in FIG. 2;

FIG. 13 is an enlarged portion view taken from encircled portion “13,” in FIG. 3;

FIG. 14 is an enlarged portion view taken from encircled portion “14,” in FIG. 3; and,

FIG. 15 is an enlarged portion view taken from encircled portion “15,” in FIG. 3.

The dash-dash broken lines in the drawings depict portions of the photo booth that form no part of the claimed design. The dot-dash broken lines represent boundaries of the enlarged portions and form no part of the claimed design.

1 Claim, 15 Drawing Sheets
